WASHING MACHINE

Fred A. Conterman, Jamestown, N. Y., assignor to
Blackstone Manufacturing Company, Inc.,
Jamestown, N. Y., a corporation of New York

Application August 6, 1936, Serial No. 94,626

6 Claims. (Cl. 248—146)

This invention relates to improvements in a supporting member or base for a washing machine tub.

The preferred embodiment of the invention discloses a leg supported base adapted to mount a washing machine tub. The base is annular and is either stepped or tapered to provide different diametered openings at opposite ends thereof. Suitable legs are fitted to the central part of the base, thus enabling use of said base with either the small or large diametered opening, serving as a mounting for a small or large diametered tub.

One of the objects of the invention lies in the provision of a base and supporting legs for the tub of a washing machine.

Another object of the invention lies in the provision of a base member which is invertible to accommodate tubs of different diameters.

Another object of the invention lies in the provision of a base to which supporting legs are removably secured.

Another object of the invention lies in the provision of a tub base and legs, the base being invertible with respect to the legs to mount either of two sizes of washing machine tubs.

Other and further objects of the invention will be more fully understood from a consideration of the following specification taken in conjunction with the accompanying drawing and in which,

Fig. 1 is a side elevation of a leg supported washing machine base adapted to accommodate a large diametered tub;

Fig. 2 is a side elevation of a leg supported washing machine base, in inverted position to that shown in Figure 1, and adapted to accommodate a small diametered tub;

Fig. 3 is an enlarged vertical sectional view of a portion of the base and supporting leg of the structure shown in Figure 1;

Fig. 4 is an enlarged vertical sectional view of the connection between the base and supporting leg of the structure shown in Figure 2;

Fig. 5 is a perspective view of one of the legs showing the parts by which the leg is secured to the tub base; and

Fig. 6 shows a modification of the means for securing a leg to the tub base.

Reference is had to the drawing wherein is shown a part of a washing machine generally indicated by the reference numeral 10. The machine includes a cylindrical tub 11, base 12, and legs 13. The base 12 is in the form of a cylinder, open at both ends. The opening at one end

is of greater diameter than the opening at the other end, this difference in diameter being obtained as shown in the drawing, by provision of a series of steps 14, 15, and 16, or in any other practical manner, as for example, by provision of a cylinder having tapered walls. The end of the base, defined by the stepped portion 14, when said end is lowermost (Figure 4), terminates in an inwardly directed flange 18. The other end of the base defined by the stepped portion 16, when this end is lowermost (Figure 3), terminates in an inwardly directed flange 19. The base member 12 is provided with two different diametered openings for the purpose of inverting it to accommodate either of two different sized tubs. When it is planned to use the base with a small diametered tub, stepped portion 14 is lowermost and flange 18 is adapted to rest upon the supporting legs hereinafter described. Similarly, when it is desired to support a large diametered tub on the base 12, stepped portion 16 is lowermost and a flange 19 is provided to mount the base on suitable legs. It will, therefore be understood that the flange 18 and 19 is formed only when it is determined with which size tub the base 12 is to be utilized.

The legs 13 are so constructed that they may be secured to the base 12 regardless of which end of said base is uppermost. Each leg 13 is generally channel shaped and comprises a base wall 21 and side walls 22. The upper end of the leg is closed by a curved wall 23 which may or may not be integral with the side and base walls. The lower end of the leg is closed by a further wall 24 which serves to support a housing for a caster 25. The side walls 22 are of gradually increased width from the lower wall 24 to a point slightly above the longitudinal center of the leg. At this point the walls are cut away to form shoulders 26 and then continue upwardly to the wall 23, the edges 27 thereof being at a slight incline to the base wall 21. It will be understood that the distance from shoulders 26 to the wall 23 of the leg is approximately that of the combined width of two of the stepped portions of the base 12, the purpose of this being hereinafter more fully brought out. Adjacent the upper end of the leg 13 is a bolt 28, having a head 29 secured in any suitable manner as by welding, to the inner face of the base wall 21. Either of two different length spacers or sleeves 31 and 32 are adapted to be mounted on the bolt 28. These sleeves serve to adapt the leg for mounting on the base in either position thereof. Adjacent the shoulders 26 is a pair of strap bolts 33.

which are secured to the walls 22 in any suitable manner as by welding. These bolts project beyond shoulders 26, at an angle thereto, and serve as a means for securing the leg to the lowermost 5 stepped portion of the base.

Reference is now had particularly to Figure 4 of the drawing which shows the base in a position to mount the smaller diametered tub 20. It will be noted that leg 13 is so mounted with 10 respect to the base 12 that the stepped portion 14 abuts the edges 27 of walls 22, and flange 18 of said portion rests on shoulders 26. The space between the end wall 23 of the leg and the stepped portion 15 is closed by a resilient filler 34 which 15 is provided with a suitable opening 35 through which spacer 31 and bolt 28 project. Spacer 31 is of a length to extend from the head 29 of the bolt to the outer face of portion 15. A suitable opening is made centrally of the portion 15 and 20 a nut 36 secures the upper end of the leg to this portion. Two openings are formed in the angle produced by the meeting edges of flange 18 and stepped portion 14. Bolts 33 project through 25 these openings. V-shaped washers 37 are mounted on bolts 33, and suitable nuts 38 secure the central portion of the leg to the stepped portion 14.

Figures 3 and 6 of the drawing show the base 12 in a position to mount the larger diametered 30 tub 11. In this instance the shorter sleeve 32 is mounted on bolt 31, one end of the sleeve abutting the stepped portion 15. The end wall 23 of the leg also abuts the portion 15 adjacent its shouldered connection with stepped portion 14. 35 A suitable opening is made in the stepped portion 15 through which bolt 31 projects, being secured by nut 36. With the base in this position, stepped portion 16 is slightly removed from the edges 27 of walls 22 of the leg. In some instances, it may be found more suitable to utilize 40 a bolt 39 as a means of securing the leg to the stepped portion 16. This bolt is formed with a head 40, welded or otherwise suitably joined to the wall 21 of the leg, and is in all respects similar to bolt 28. A flexible filler 42 fills the gap 45 between the edges 27 of walls 22 and stepped portion 16. Bolt 39 is projected through a suitable opening in the stepped portion and secured by nut 43. It will be understood that with the 50 base in this position flange 19 abuts shoulders 26.

The structure disclosed in Figure 6 of the drawing is a combination of the structural details shown in Figures 3 and 4. In this modification strap bolts 44 similar to strap bolts 33 are secured 55 to walls 22 and project substantially perpendicular to the base wall 21. Bolts 44 project through suitable openings in stepped portions 14 or 16, being secured against removal by nuts 45. The upper bolt and sleeve, in this figure, utilized 60 to secure the leg to the central stepped portion 15, is identical with bolt 28 and sleeve 32 and, therefore, bears these reference numerals.

From the foregoing it will be understood that the present invention contemplates provision of a 65 stepped or tapered base having different diametered openings for the purpose of mounting different diametered tubs, and that regardless of the position of the base, legs of the same design and structure may be utilized. It will also be understood that modifications in the number of steps in the base, number and position of bolts 70 for securing a leg to the base, and other variations or adaptations of the structure herein shown and described are contemplated in so far 75 as these modifications are within the spirit and

scope of the invention as defined in the hereunto annexed claims.

Having thus set forth my invention what I claim as new and for which I desire protection by Letters Patent is:

1. In a washing machine, a base member adapted to mount a tub, a plurality of stepped portions in the walls of said member, said stepped portions providing different diametered openings at opposite ends of said member, a supporting leg 10 for said member, the upper portion of said leg abutting one of said stepped portions, a filler interposed between another of said stepped portions and the adjacent edge of said leg, and means rigidly securing said leg to two of the 15 stepped portions of said member.

2. In a washing machine, a cylindrical base member adapted to mount a tub, a plurality of stepped portions in the walls of said member, said stepped portions providing different diametered openings at opposite ends of said member, an inwardly directed flange on the lower edge of 20 said member, a leg for supporting said member, shoulders on said leg forming a seat for the flange of said member, the portion of said leg above 25 said shoulder being engaged with one of the stepped portions of said member, a resilient filler located between the next adjacent inwardly offset stepped portion of said member and the upper portion of said leg, and bolt means projecting through said filler and two stepped portions of said member for rigidly securing said leg to said member.

3. An invertible base member for washing machine tubs, said member being generally cylindrical and having a plurality of stepped portions in the walls thereof, said stepped portions providing openings of different size at opposite ends of said member, a supporting leg for said member, one of the stepped portions being adapted 40 to have full width abutment with a portion of said leg, another of said stepped portions being spaced therefrom when said member is in upright or inverted position, a resilient filler between said leg and the spaced stepped portion, and means 45 compressing said filler and rigidly securing said leg to the spaced stepped portion.

4. An invertible base member for washing machine tubs, said member being generally cylindrical and having a plurality of outwardly projected annular stepped portions providing openings of different size at opposite ends thereof, a supporting leg for said member, the upper portion 50 of said leg being adjacent at least two stepped portions of said member and in contact with one 55 of said stepped portions when said member is in upright or inverted position, means interposed between said leg and another of said stepped portions, and further means rigidly securing said leg to at least one of said adjacent stepped portions. 60

5. An invertible base member for washing machine tubs, said member being generally cylindrical and having a plurality of outwardly projected annular stepped portions providing openings of different size at opposite ends thereof, a supporting leg for said member, the upper portion 65 of said leg being adjacent two stepped portions of said member, one of said stepped portions being in contact with said leg, and the other of said stepped portions being spaced therefrom 70 when said member is in upright or inverted position, a filler occupying the space between said leg and the spaced stepped portion, and means rigidly joining said leg to said spaced stepped portion.

6. An invertible base member for washing machine tubs, said member being generally cylindrical and having a plurality of outwardly projected annular stepped portions providing openings of different size at opposite ends thereof, a supporting leg for said member, the upper portion of said leg being adjacent at least two stepped portions of said member, said member,

in one position, having the lowermost stepped portion engaged with said leg and, in another position, the second stepped portion engaged with said leg, and means rigidly securing said leg to the stepped portion of said member with which it contacts. 5
